UNITED STATES PATENT OFFICE.

HENRY A. FLETCHER, OF LOWCA ENGINE WORKS, NEAR WHITEHAVEN,
COUNTY OF CUMBERLAND, ENGLAND.

RAILWAY-RAIL.

SPECIFICATION forming part of Letters Patent No. 249,328, dated November 8, 1881.

Application filed January 24, 1881. (No model.) Patented in England June 11, 1880.

To all whom it may concern:

Be it known that I, HENRY ALLARSON FLETCHER, of Lowca Engine Works, near Whitehaven, in the county of Cumberland, England, have invented a new and useful Improvement in the Permanent Way of Railways and Tramways, of which the following is a specification.

My improvement relates to rails used for the permanent way of railways and tramways, and has for its object to obtain more solid and firm support to the rails without materially increasing the material.

The invention consists in an improved form or shape, the base or lower flange being extended or spread out where it rests upon the sleeper or other support, instead of being made, as usual, of a parallel form throughout. The rail may also be strengthened where it rests upon the sleeper or other support by thickening it at the extension.

In the accompanying drawings, forming part of this specification, Figures 1 to 5 are plan views of rails having my improvement applied, 25 and showing various modifications. Figs. 7 to 11 are cross-sections of the several rails, respectively.

Similar letters of reference indicate corresponding parts.

30 A is the rail, a the usual flange, and b the extension of the flange, constituting my improvement. In Figs. 1 and 7 the flange is spread equally on both sides. In Figs. 2 and

8 the extension is on one side only. In Figs. 3 and 9 the flange is shown spread or extended at both sides, but inclined. In Figs. 4 and 10 the extended or spread-out portion is at opposite sides alternately. In Figs. 5 and 11 the extension is shown in connection with the thickened portion.

The rail rests upon the sleeper or other support at its extended portion, so that a broad and firm support is given to the rail, with addition of only a small amount of material, and the rail is strengthened at those points.

In order to roll rails with feet of the curvilinear form shown, it is only needful to cut flat faces in the last groove of the rolls through which the rail passes. These flats may be replaced by curved or wavy forms, if it is desired to produce feet of other shape, such as a parallel form, or one approaching it.

Having thus described my invention, I claim as new and desire to secure by Letters Patent—

In railways and tramways, the rail A, having the side juttings or projections, b, at the place where they rest on the sleepers, as described.

The above specification signed by me this 24th day of June, 1880.

H. A. FLETCHER. [L. S.]
